Primary Examiner — T. Chase Nelson(74) *Attorney, Agent, or Firm* — Mintz Levin Cohn Ferris Glovsky and Popeo, P.C.(57) **CLAIM**

The ornamental design for a footwear sole, as shown and described.

DESCRIPTION

The sole FIGURE is a bottom plan view of the exterior of an article of footwear, showing the new design for a footwear sole.

The broken lines shown in the figures represent illustrative portions of the article of footwear that form no part of the claimed design. The claimed design is flat and in a single plane.
